Fig. 3

Fig. 5

Fig. 4

Figure 1 is a perspective view of a fishing lure showing my new design, the lure being adjusted to provide a wriggling action;

Figure 2 is a similar perspective view thereof with the lure being adjusted to provide a spinning action;

Figure 3 is a top plan view of the body portion shown in Figure 1;

Figure 4 is a side elevational view of the body portion shown in Figure 1; and

Figure 5 is a front elevational view of the body portion.

The dominant feature of my design resides in the full line portion of the drawing.

I claim:

The ornamental design for a fishing lure, substantially as shown and described.
